(57) **CLAIM**

We claim the ornamental design for an electronic device, as shown and described.

DESCRIPTION

FIG. 1 is a front perspective view of an electronic device showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlarged view of the encircled portion in FIG. 6; and,

FIG. 9 is another front perspective view thereof in which the electronic device is shown in an open position.

The evenly dashed broken lines in the figures depict environmental subject matter and form no part of the claimed design.

The dot-dashed broken lines in the figures represent a boundary line and form no part of the claimed design.

The dot-dot-dashed broken lines encircling portions of the claimed design that are illustrated in enlargements form no part of the claimed design.
